UNITED STATES PATENT OFFICE.

WILLIAM GRIMSHAW, OF CHICAGO, ILLINOIS.

CEILING PLATE.

Application filed August 2, 1926. Serial No. 126,705.

This invention relates to ceiling plates such as are commonly used for imparting a finish to a wall or ceiling where a pipe or rod projects through the same, as in automatic sprinkler, lighting and other installations.

The object of the invention is to provide a self-locking ceiling plate, which is simple in construction, attractive in appearance, which is inexpensive to manufacture, and which may quickly and conveniently be installed in position.

Considered broadly, a wall or ceiling plate embodying my invention and improvements is made of resilient sheet material, preferably sheet steel of about 20 gage, provided with a hole and with slits which extend outwardly from said hole, forming spring segments connected at their outer ends, said plate being dished and the opening therein being smaller than the member with which it is designed to be used. Preferably, also, the portion of the plate in which the hole is formed is substantially flat.

In use, my improved ceiling plate is adapted to be adjusted to a member—rod or pipe—with which it is designed for use so that said member will enter the hole therein from the concave side of the plate. Being slightly smaller than said member, it is obvious that the operation of adjusting the ceiling plate to said member will expand the hole therein, forcing the segments of the plate apart and causing them to grip said member with strong frictional engagement which, while permitting movement of the ceiling plate to adjust it to said member, will effectually prevent movement of said ceiling plate to withdraw it therefrom.

My invention also comprises the various other features and details of construction hereinafter described and claimed.

In the accompanying drawings in which my invention is fully illustrated,

Figure 1 is a plan view of the concave side of the ceiling plate;

Figure 2 is a sectional view thereof on the line 2—2 of Fig. 1;

Figure 3 is a diagrammatic view illustrating the manner of applying my improved ceiling plate in use; and

Figure 4 is a plan view from the position 4—4 of Fig. 3.

Describing the invention with particular reference to the drawings, my improved ceiling plate, designated as a whole A, is made

of suitable resilient sheet material, preferably sheet steel of approximately 20 gage, said plate being dished, one side thereof being concave and the other convex. As shown, said plate is circular in plan view, but the shape thereof is immaterial and may be varied as desired without departure from my invention.

Formed in said plate, preferably in the center thereof, is a hole or opening 1 and extending outwardly therefrom, preferably on radial lines, are slits 2, forming spring segments 3 which are connected at their outer ends.

Preferably, also, the portion of the plate A in which the hole 1 is formed is substantially flat.

In use, the plate A is adapted to be adjusted to a member, as a rod or pipe 4, projecting from a wall or ceiling, indicated at 5, so that said member 4 will enter the hole 1 from the concave side of the plate. In accordance with my invention, the hole 1 is slightly smaller than the member 4 so that the act of adjusting said plate to said member will expand said hole, forcing the free ends of the segments 3 apart and causing them to grip the member 4 with strong frictional engagement which, while permitting movement of the plate on said member into adjusted position, will effectually prevent movement of said plate in a direction to withdraw it from said member, in an obvious manner.

My improved ceiling plate may conveniently be formed by usual stamping processes and the shape thereof in cross section may be variously modified, as desired, without departure from my invention.

I claim:

1. A wall or ceiling plate for the purpose specified, comprising a plurality of spring segments connected together at their outer ends, said plate being dished and the edges of the inner ends of the segments thereof defining a hole in said plate adapted to receive a member in association with which said plate is designed to be used and which is normally smaller than said member, and the inner ends of different segments comprising opposed portions, the relation being such that when a plate is applied to a member the edges of the inner ends of said segments will directly engage said member.

2. A wall or ceiling plate as specified in claim 1, in which the plate is made of thin

sheet metal and is provided with slits which extend outwardly from the hole therein on substantially radial lines forming the segments of said plate.

5. 3. A wall or ceiling plate as specified in claim 1, in which the end portions of said segments which define the hole in the plate are substantially flat.
4. A wall or ceiling plate as specified in

claim 1, in which the end portions of said segments which define the hole in the plate are flat and positioned substantially in the same plane.

In witness that I claim the foregoing as my invention, I affix my signature this 27¹⁵ day of July, A. D. 1926.

WILLIAM GRIMSHAW.
